N. J., and Roy H. Zinkil, Oak Park, Ill.

Application June 18, 1938, Serial No. 214,429

9 Claims. (Cl. 4—10)

This invention relates to a swivel type of plumbing fixture which can be placed within a recess or the wall of a building or in a railroad car or other vehicle where space is relatively limited and which, when in use, may be conveniently swung outwardly to project into the interior of the room. When not in use the fixture may be swung inwardly so as to be concealed within either the interior of the wall or else positioned under suitable furniture and the like, such as a railway car seat, for example.

The principal object is to provide for the swivelable fixture to be hidden from view when desired and yet permit almost immediate utilization when required.

Another important object lies in providing for a fixture of this type in which the normal load is easily carried by a sturdy construction employing a combined fitting and roller and in which means are provided for a suitable swing joint functioning in a liquid-tight manner.

Another object lies in providing for a fixture of the swiveling type which may be conveniently installed either for a left-hand or right-hand installation, using a relatively cheap base plate of simple design.

Another object lies in providing for a fixture of the character described in which the flushing means is relatively closely positioned adjacent to the bowl proper, permitting the desired swiveling movement to take place without subjecting the closet bowl and also the flushing mechanism to an objectionable strain.

Another object lies in providing for a suitable shield or apron around the exterior periphery of the bowl whereby the user's clothing may avoid contact with the operating mechanism.

Other objects and advantages become more readily apparent upon proceeding with the following description in connection with the drawings, in which

Fig. 1 is an exterior perspective view of a left-hand installation showing the flushing mechanism mounted with respect to the base plate and waste connection, with a protecting apron shown in fragmentary section.

Fig. 2 is a side perspective view of the fixture slightly in plan elevation taken on the opposite side of the device as described in connection with Fig. 1, and with the said apron likewise shown in partial section.

Fig. 3 is a plan exterior view showing a right-hand closet bowl and the supporting means connected to a partial actuating mechanism, with the flushing valve and supply on the right-hand

side and with the bowl suitably modified to accommodate the above installation. Here it might be added that the actuating means illustrated is not a part of this invention but is being claimed separately in another application, Serial No. 237,435, filed October 28, 1938.

Fig. 4 is a side fragmentary sectional view of the device described in connection with Fig. 3, showing the manner in which the closet bowl exemplifying our invention may be installed beneath a railroad car sofa or seat, and also the manner in which the water flow connections are made between the bowl and the discharge outlet therefrom.

Fig. 5 is a schematic outline tracing the flow of water from the supply and through the bowl.

Similar reference characters refer to similar parts throughout the various views.

Referring to Fig. 1, the closet bowl generally designated as 1 is shown as having a conventional flushing valve 2 mounted at its side, the latter being supplied with the usual inlet stop valve 3 and the inlet connection or pipe 4 for attachment to a source of water supply (not shown). The rearward portion of the bowl is provided with an integral flange 5 serving for its purpose as a connection to a suitable discharge elbow fitting 6 which is mounted by means of a rotatable shaft 7 to a pair of supporting brackets 8, the outlet fitting 6 having the usual connection to a trap or septic tank (not shown) while the bracket 8 is connected to a base or floor plate 9 for attachment to a floor or the like. The discharge fitting 6 serving as a support for the bowl by means of its attachment to the flange 5, is provided with a suitable roller 11 arranged to travel upon the base plate 9, as indicated, and having suitable stops 12 and 13 (the latter being visible only in Fig. 2) to limit its rotation from the outward position within the room to the inward position within the recess. The foregoing outline sketches rather briefly the general manner in which the bowl is mounted for use, say, on a railroad car or where space is at a premium so that the closet bowl may be swivelably moved out of the way, as desired.

Proceeding now with a more detailed description of the structure exemplifying our invention, the bowl 1 is provided with a conventional rim 14 with a horizontally extending surface and the rearwardly extending portion 15, the purpose of which is to serve as a shield against wearing apparel becoming soiled by contact with the roller 11 and the joint between the discharge fitting 6 and the flange 5 of the bowl 1. Prefer-

ably, as indicated, the side of the rim 14 is further provided with suitable apertures 16 for purpose of attachment of a protecting apron 17 which is shown as being broken away, but which 5 extends around the bowl so as to enclose the same separate from the flushing valve operating mechanism 2.

As more clearly shown in Fig. 4, the bowl 1 is provided with an inner rim flush 18, the water 10 being supplied to the chamber 19 by means of the usual flush valve 2. The water is thereafter divided into two paths of flow; one to the rim flush chamber 21 and the other by means of channels (not shown) on the side of the bowl 15 into the jet chamber 22, allowing for a jet 23 to be formed for the evacuating of the bowl contents and subsequent flushing thereof. For purpose of greater security, a plug 24 is usually provided at the lower portion of the jet chamber so 20 that in the event it is desired to drain the same, of example, during freezing weather, this may be done conveniently, but this provision is not a part of our invention. The operating means of the flush valve 2 is of the conventional non-hold-open type referred to in expired United 25 States Patent No. 1,114,398, granted October 20, 1914, and the details of its internal mechanism are not therefore shown, and also since the use of this type of valve does not add anything 30 particularly insofar as our invention is concerned.

Upon depressing the pedal 25, the valve 2 will then be opened and thus allow for water from the inlet to flow to the rim flush and to the jet means to pass within the bowl.

35 As previously explained, the closet bowl 1 is provided with the connecting flange 5 and, as more clearly shown in Fig. 4, the outer portion of the discharge 10 of the bowl has an angularly extending grooved portion 20 provided 40 with packing 26. A contact is maintained with the peripheral end 27 of the discharge fitting 6 and held in pressure-tight relation by means of the bolts and nuts 28 and 29 respectively, producing an effective joint in a relatively simple 45 manner. The discharge fitting 6, which is preferably made of steel or of a similar substantially strong material, is provided with an extending bracket 31 serving as a journaling member for the rotatable shaft 7, the latter member 50 having a collar 40 for engagement with an axially aligned journaling member 32 which may be made integral or else may be connected by means of the bolts 33 to the supporting brackets 8, the latter members being fixedly mounted by 55 means of the bolts 34 to the base plate 9. It will be noted, in referring to Fig. 1, that the base plate 9 is provided with an extension portion 30 and a drilled bracket mounting 35 provided with the desired holes 36 for purpose of attaching an actuating 60 ing mechanism as previously referred to.

As shown more clearly in Figs. 3 and 4, a suitable system of actuating mechanism comprising levers, hinges and gears may thus be provided for swivelably moving the closet bowl from an 65 open or operative position to a closed and inoperative position. However, as stated, the latter mechanism application is not a part of this invention and is covered by a separate application and therefore will not be described in detail 70 herein but will merely be generally referred to.

However, aside from the bracket supporting means just described, a more important aspect of our invention lies in the manner of providing an effective liquid-tight swivel joint. Therefore, 75 referring now to Fig. 4, the lower portion of the

discharge fitting 6 is provided with a flange 37 bearing closely upon the surface 38 of the base plate 9. The discharge fitting 6 has a downwardly projecting extension 39 journalled within an aperture 41 about which a bushing 42 is 5 rotatably mounted, the latter member shouldering upon the base plate 9, as at 38, and being positioned between the flange 37 and the annular portion of the aperture of the base plate 9. The bushing 42 is preferably provided with the annularly positioned water sealing grooves 44, the purpose of the latter being to provide a sealed connection for the discharge outlet in its journaling arrangement with the base plate.

In order to understand more clearly the manner in which the bowl is flushed by means of the flush valve 2, attention is now directed to the schematic outline showing the flow of water from the water supply to the bowl, as shown in Fig. 5, in which, as indicated by the arrows, water enters the inlet supply connection 4 passing through the valve stop 3, then into the flush valve 2 operated by the pedal 25, and thence passing into the bowl manifold chamber 19 which, as indicated, is divided into the jet flush chamber 22 and the rim 25 flush chamber 21, the latter being provided with flushing apertures 40 around the periphery of the inner rim 18.

Therefore, it will be apparent that our invention is principally directed to a swivelable bowl 30 support and suitable attaching means, and further, that the particular manner of exemplifying our invention is capable of several modifications falling within the spirit of our invention. We desire therefore to be limited only to the extent of the claims appended hereto interpreted in the light of limitations exerted by the state of the art.

We claim:

1. In a swiveling type closet bowl, supporting 40 means for the said closet bowl comprising a hollow discharge member cooperating with an apertured base plate, the said discharge member having an upper end portion attached to the said closet bowl and an angularly positioned lower end 45 portion journalled for rotative movement within the said base plate, independent spaced apart supporting means upon the said plate cooperating with the said discharge member to maintain the latter in axial alignment with the said apertured portion of the said plate.

2. In a closet bowl assembly of the swiveling type, comprising a closet bowl, supporting means therefor including a hollow discharge fitting member attached to the said bowl, the latter member being rotatable on a vertical axis and having combined roller and journaling means for effecting the swiveling movement of the said bowl in a substantially horizontal plane, the said roller means being radially disposed from 60 said journaling means.

3. In a closet bowl assembly of the swiveling type described, comprising a closet bowl, supporting means therefor, a base plate for the said supporting means, the said supporting means including a hollow discharge fitting member, the latter member having combined roller and journaling means providing for arcuate movement of the said bowl in a substantially horizontal plane, the said base plate having a plurality of bracket 70 members forming a common journaling means for the said fitting member.

4. In a closet bowl assembly of the swiveling type described, comprising a closet bowl, a base plate therefor, supporting means for the said 75

bowl including an arcuately movable hollow discharge fitting and bracket supports mounted upon the said base plate cooperating with the said fitting, the said fitting being journally disposed within the said base plate and having roller means suitable for arcuate travel upon the said plate.

5. In a closet bowl assembly of the swiveling type described, comprising a closet bowl, supporting means therefor comprising a hollow discharge fitting member and bracket members, the said fitting member having combined journaling means for effecting the swiveling movement of the said bowl, the said journaling means including a shaft member having one end journaled within the said fitting member and its other end portion journally supported by the said bracket members.

6. In a closet bowl assembly of the swiveling type, comprising a closet bowl, supporting means therefor including a hollow discharge fitting member of angular form, the latter member having journaling means for effecting the swiveling movement of the said bowl, and a depending skirt member around a portion of the upper periphery of the said bowl.

7. In a closet bowl assembly of the swiveling type, comprising a closet bowl, supporting means therefor including respectively a discharge fitting member having passages in angular relation and bracket members, the said fitting member having combined actuating and journaling means for effecting the swiveling movement of the said bowl, the said journaling means including a shaft member having one end journaled within the said fitting member and its other end portion journally supported by the said bracket

members, the said actuating means including an extended portion upon the said fitting member suitable for connection to an independent actuating mechanism.

8. In a swiveling type of closet bowl comprising a bowl having jet and rim flush means, the said bowl being mounted for swiveling movement in a substantially horizontal plane, supporting means for the said closet bowl, the said supporting means comprising a fitting member having an angularly disposed discharge passage from the said bowl, the said fitting member being mounted for rotation on a vertical axis upon a base plate member having journaling means for the said fitting member, the said journaling means comprising a unitary assembly having angularly disposed brackets mounted upon the said base plate member to support the said fitting member axially from a plurality of directions.

9. In a closet bowl assembly of the swiveling type, comprising a closet bowl, supporting means therefor comprising a unitary assembly including a hollow discharge fitting member having respective angularly disposed inlet and outlet passages, a shaft extension upon the said fitting member substantially parallel to said outlet passage and cooperating with the said supporting means to provide for the swiveling movement of the said bowl in a substantially horizontal plane, bracket members engaging the said shaft extension and serving as journaling means therefor, a base member supporting said bracket and fitting members.
